Primary Examiner — Eric Goodman*Assistant Examiner* — Luqman McNeil(57) **CLAIM**

I claim the ornamental design for an animal neck covering, as shown and described.

DESCRIPTION

FIG. 1 is a perspective view of an animal neck covering worn by an animal;

FIG. 2 is a perspective view of an animal neck covering in a closed state;

FIG. 3 is a perspective view of an animal neck covering in a closed state;

FIG. 4 is a top edge view of an animal neck covering in an open state;

FIG. 5 is a plan view of an animal neck covering in an open state;

FIG. 6 is a bottom view of an animal neck covering in an open state;

FIG. 7 is a bottom edge view of an animal neck covering in an open state;

FIG. 8 is a side edge view of an animal neck covering in an open state; and,

FIG. 9 is a side edge view of an animal neck covering in an open state.

The broken line showing is included for the purpose of illustrating portions of the article and forms no part of the claimed design.
